Inventor.

George H. Blanchard,
By ~~Attew & Totten~~ attorney

UNITED STATES PATENT OFFICE.

GEORGE N. BLANCHARD, OF SAN FRANCISCO, CALIFORNIA, ASSIGNEE TO COLMAR BURNER COMPANY, OF SAN FRANCISCO, CALIFORNIA, A CORPORATION OF CALIFORNIA.

SAFETY MECHANISM FOR FURNACES.

Application filed December 13, 1922. Serial No. 606,703.

To all whom it may concern:

Be it known that I, GEORGE N. BLANCHARD, a citizen of the United States, residing at the city and county of San Francisco, and State of California, have invented certain new and useful Improvements in Safety Mechanism for Furnaces, of which the following is a specification.

It has been found advisable, if not necessary, to provide in heating apparatuses, particularly hot air furnaces, a type of control adapted to reduce the intensity of the heat in the firebox at such times as all the hot air outlets are closed, thus preventing the overheating of a furnace to such a point as to fire the building.

My present invention relates to an automatic control designed particularly for incorporation within a hot air furnace to be acted on by the temperature of the air in one of the hot air outlets whereby the intensity of the heat in the firebox is reduced on the temperature of the air exceeding a predetermined degree.

Among the objects of this invention is to provide a construction which is operated by the melting of an element acted on by the temperature of the heated air and known to fuse on the temperature exceeding a certain degree; one wherein the element may be readily renewed after it has once fused; one containing an indicator denoting when the element has fused; and one wherein the fusing of the element permits the operation of a weighted member to actuate a movable member for varying the intensity of the heat in the firebox on the air temperature increasing beyond a predetermined degree.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein:-

Fig. 1 is a view in front elevation of the preferred embodiment of my invention applied to a hot air furnace with the center of the lever broken away illustrating the instructions contained on the plate and exposed when the lever drops.

Fig. 2 is a sectional view illustrating particularly a fusible member in the tubular support.

Referring more particularly to the several views of the drawings, wherein like characters of reference designate corresponding parts, 1 indicates the wall of a firebox 2 which is adapted to heat the air passing upwardly in the direction of the arrows 3 in the flue or duct 4 adjacent to said firebox. In this present disclosure, the firebox is adapted to be heated by a hydrocarbon fuel burner 5, the fuel feed to which is supplied through a valve controlled pipe 5¹ by a pump 5² operated by an electric motor 5³; the operation of which is in turn controlled by a switch 6 preferably positioned on the front wall 7 of the furnace. It is to be understood that this switch element 6 is broadly illustrative of a control for the heating element, as if desired the same may be in the form of a valve for controlling the fuel supply, or a damper for controlling the air for combustion admitted into the firebox 2, or an additional supply of air into the duct 4. The switch 6 carries a movable member 8 and with the same is adapted to coat the bifurcated operating member 9 carried by a member 10 extending through a slot or opening 11 in the furnace front wall 7. The member 10 is secured to a weighted operating rod 12 vertically movable in a guide 13 at its lower end, and to the upper end of said rod 12 is pivotally connected as at 14 the free end of a lever 15. The lever is carried on the inner end of a bearing 16 fulcrum 16 passing through the wall 7, and to the front end of said member 16 is secured an operating lever 17 carrying on its free end a finger grip 18. It will be observed

that the entire weight of parts 9, 10, 12, 16, 18

17 and 18 is adapted for downward gravity movement to actuate the member 8, and thereby reduce the intensity of the heat in the firebox 2. The bearing fulcrum 16 is carried by a plate 19 detachably secured over an opening 20 in the furnace front wall 7, and inwardly from said plate extends an open ended tubular guide 21 provided with a stop 22 at its inner end in close proximity to the rod 12, said guide terminating at a point immediately below the lever 15 when the same is in its fully elevated position, as indicated in Fig. 2.

Removably inserted into the guide 21 is an element, as for example a metal 23, adapted for fusing or melting at a known temperature, said element 23 when fully inserted into said guide is adapted to lie beneath the lever 15 and retain the rod 12 in its elevated position. The exposed end of the element 23 adapted for fusing on the temperature of the air within the duct 4 increasing above the melting point of the element, is adapted to release the lever 15, permitting the weight of the lever and its associated parts to drop by gravity and actuate the member 8 to cause a reduction in the heat intensity of the firebox. On the dropping of the lever, the member 17 is adapted in its movement to expose an indication on the plate 19, to the effect that the fuse or element 23 needs replacement. After the actuation of the member 8 on the fusing of the element 23, the operator grasps the handle 18 to raise the lever 15 above the inner end of the guide 21, inserts a new element or fuse within the guide so that the same will support the lever 15 and then raises the movable member 8 after which time the apparatus is again adapted for operation. If desired, the movement of the free end of the lever

15 may be controlled by the fixed upper and lower stops 24 and 25.

Having thus described my invention, what I claim as new and desire to protect by Letters Patent of the United States is:—

1. In combination with a hot air duct, an electric switch, mechanism for operating said switch, a horizontally disposed support projecting into the said duct through its wall, and a fusible member removably positioned within and projecting into said duct beyond the inner end of said support for supporting and retaining said mechanism in inoperative position, said member adapted to fuse on the temperature in said duct attaining a predetermined degree for releasing said mechanism.

2. In combination with a hot air furnace provided with a firebox and an air circulating duct heated thereby, a movable means adapted when operated for controlling the fire in said firebox, a movable rod for operating said movable means, an adjustable connection between said rod and movable means, an open ended tubular guide extending horizontally into the duct, the outer end of said guide lying exteriorly of the duct, a fusible member insertable into said guide through its outer end, the inner end of said fusible member adapted to project beyond the end of said tubular guide to retain said rod in an elevated inoperative position, and adapted to fuse to release said rod on the temperature of the air within said duct exceeding a predetermined degree, and means exteriorly of the furnace and associated with the rod to permit the manual raising of said rod.

In testimony whereof I have signed my name to this specification.

GEORGE N. BLANCHARD.
